(57) **CLAIM**

The ornamental design for an electronic media cutter, as shown and described.

DESCRIPTION

FIG. 1 is a top plan view of an electronic media cutter which forms our new design;

FIG. 2 is a bottom plan view thereof;

FIG. 3 is a front elevational view thereof;

FIG. 4 is a rear elevational view thereof;

FIG. 5 is a left side elevational view thereof, this side and the opposite right side being mirror images; and;

FIG. 6 is a perspective view showing the front, top and right side thereof.

The broken lines in the drawings depict unclaimed environmental subject matter.
